UNITED STATES PATENT OFFICE

HUGO MOCK, OF NEW YORK, N. Y.

KEY CAN OPENER

Application filed December 14, 1929. Serial No. 413,970.

This invention relates to improvements in key can openers and more particularly to improvements in the keys by which the ordinary type of food container cans are opened and in the parts of the can co-operating with the key in the opening of same.

A principal object of my invention is the provision of an improved key can opener in which positive means are present so that the opening or ripping of the can will always take place in a pre-determined direction along the lines of scoring on the body of the can.

Further objects of my invention are the provision of the key and co-operating of the can by which the key will be more firmly held than in the present type of opener and in which the key will be held at all times at a fixed angle to the line of opening of the can.

Further objects of my invention will be apparent from the specification and drawings in which,

Fig. 1 is a perspective view of a can having a tongue thereon operable by my improved key.

Fig. 2 is a perspective view of an improved key embodying one form of my invention.

Fig. 3 is a vertical section of the part of the can with a tongue attached thereto.

Fig. 4 is a sectional view along the line 4—4 of Fig. 2.

Fig. 5 is a vertical section of the portion of the can and tongue with my improved opener inserted therein.

Fig. 6 is an enlarged sectional view along the line 6—6 of Fig. 4.

Fig. 7 is a vertical section of the can, tongue and key, showing the manner of operating the key.

Fig. 8 is an enlarged plan view of the tongue showing the slot therein.

Fig. 9 is a sectional view showing the form of modified key.

I show in Fig. 1 a conventional can A with a tongue B and claim no novelty either in the form of can or tongue, excepting that I have added to the tongue a slot C which is parallel to the edge thereof and at right angles to the direction toward which the key is

turned. The top of the can A is provided with scoring lines connecting with the tongue C, the top of the can A being tearable along such scoring lines.

In Fig. 2 is shown a perspective view of my improved key which is the same as the conventional key now in use except for the projection D which is adapted to fit into and positively grip the slot C. By making the projection D fit the slot C, the key D when turned in the direction of the line of scoring will tend to keep its axis at right angles to the direction in which such key is turned and will also prevent the key from slipping off the tongue. In this way a positive grip is obtained upon the tongue which permits the opening of the can with certainty at all times.

I have shown this improvement adapted to a can in which the top is detachable but it is evident that the same improvement may be used where the can is opened on the side. It is also apparent that modifications in the tongue and in the key itself as in the form of the projections or teeth used to grip the tongue, may be made without departing from the spirit of my invention.

Having fully described my invention what I claim is:

1. A key for opening a rip strip can, said key being provided with an aperture, the interior of said aperture being provided with engaging means adapted to engage and grip the tongue of a rip strip can.

2. A key for opening a rip strip can, said key being provided with an aperture, said aperture being provided with a lug adapted to engage and grip the tongue of a rip strip can.

3. In combination, a key for opening a rip strip can, said key being provided with an aperture, said key having engaging means adjacent said aperture adapted to engage and grip the opening in the tongue of a rip strip can.

4. In combination, a key for opening a rip strip can, said key being provided with an aperture, said aperture being provided with engaging means adapted to engage and grip the slot in the tongue of a rip strip can.

5. A key for opening a rip strip can, said

key being provided with an aperture, the interior of said aperture being provided with engaging means adapted to engage reciprocal engaging means on a rip strip can.

5 6. In a rip strip can, a tongue on said can having a slot therein and a key provided with engaging means adapted to engage said slot for opening said can.

7. In a rip strip can, a tongue on said can, 10 said tongue being associated with a line of scoring by which said can may be opened, an opening on the surface of said tongue and a key fitting said tongue, said key having a member thereon fitting said opening and 15 adapted to lock the key against displacement when operated.

In testimony whereof I affix my signature,
HUGO MOCK.
